UNITED STATES PATENT OFFICE.

KARL RÖGER, OF BERLIN, GERMANY, ASSIGNOR TO MERGENTHALER LINOTYPE COMPANY, A CORPORATION OF NEW YORK.

MEANS FOR CHANGING MAGAZINES OF MULTIPLE-MAGAZINE TYPOGRAPHICAL COMPOSING AND DISTRIBUTING MACHINES.

1,123,803.

Specification of Letters Patent.

Patented Jan. 5, 1915.

Application filed March 30, 1914. Serial No. 828,223.

To all whom it may concern:

Be it known that I, KARL RÖGER, a subject of the German Emperor, residing at 33 Teltowerstrasse, Berlin, in the Empire of Germany, have invented new and useful Improved Means for Changing the Magazines of Multiple-Magazine Typographical Composing and Distributing Machines, of which the following is a specification.

10 This invention consists of improved means for changing the magazines of multiple-magazine typographical composing and distributing machines using separable pieces—matrices or type dies as the case may be—15 and is especially applicable to machines constructed and working according to the Mergenthaler system and generally known under the trade mark "Linotype." The magazines of a machine of this system, are arranged 20 columnwise one upon the other, the column being raised or lowered between a relatively fixed assembler and distributor to effect a "quick change," that is, to put any one magazine of the column into both composing position with reference to the assembler entrance and distributing position with reference to the distributor. But when the 25 column does not contain a magazine equipped with the required font of pieces one of the 30 magazines in the column must be changed, that is, it must be taken off or out of the column and a magazine equipped with the required font must be substituted for it.

The present invention is intended to provide some suitable means whereby the column in its entirety may be swung backwardly and downwardly from its operative position in the machine to permit the convenient removal of the magazines at 40 the rear. In the present instance such means are shown as consisting of two supporting frames, one of them for the "quick change," which may be termed the "shift frame," and the other one for the removal or inter- 45 change of the magazines, which may be termed the "supporting frame." In one form I have shown the supporting frame as being pivotally mounted in the shift frame, so that the former may be rocked 50 downward through the latter to permit the removal of any or all of the magazines at the rear of the machine. In another form, I have shown the supporting frame as being pivotally mounted in the machine frame,

and as carrying the shift frame and its 55 shifting mechanism. In this latter form, when the supporting frame is rocked downward, it will carry with it the shift frame, from which the magazines may be conveniently removed. It will be understood, how- 60 ever, that other forms may be employed to secure the same result without departing from the spirit of my invention, it being the essential idea to mount the column of magazines in the machine so that it can be moved 65 upward and downward to bring one or another of its magazines into operative position and so that the column in its entirety may be swung backward and downward from its normal position in the machine to 70 permit the removal of the magazines at the rear.

The accompanying figures illustrate a preferred constructional form of the application of the invention to a machine of the 75 Mergenthaler system and of a modification of that form.

Figures 1 and 2 are respectively a side elevation from the right side of the machine and Fig. 2, a plan of the said form, Figs. 3 80 and 4 being the like of the said modification.

Referring to Figs. 1 and 2, the column of magazines 1, is shown as comprising only two but may comprise any convenient number. 2 is the supporting frame and to it 85 the magazines are connected in any suitable way which will permit their convenient removal; and 3 is the shift frame. This latter has depending rods 4 sliding in sockets 5 fast on the main frame of the machine and 90 studs 6 engaged by cam grooves 7 turning about axes 8 supported in the said frame to effect a "quick change." 9 is the assembler entrance, 10, the escapements, 11, the distributor, and 12, the magazine entrance. All 95 these parts are of the known construction. The shift frame 3 is under the frame 2 and is open across its rear, the frame 2 being adapted by being narrower than it and pivoted across or near to its front edge by a 100 pivot 13 to the front edge of the frame 3, to rock down into the position shown by the dotted lines in Fig. 1 when any one or more of the magazines 1 has or have to be changed. The rear of the column and frame 105 2 are supported in the composing and distributing position by any suitable means such as a retractable horizontal rod 14 working

through the rear end of each side of the frame 3.

Referring to Figs. 3 and 4, 2^a is the supporting frame and 3^a the shift frame. In this instance the shift frame is carried by the supporting frame, the latter being pivotally connected to the machine frame, as at 18, so as to be swung backwardly and downwardly from its operative position to permit the removal of the magazines. The shift frame is pivotally connected to the supporting frame, as at 15, so as to be movable relatively thereto to locate one or another of the magazines 1, 1, in operative relation to the assembler entrance 9. The means shown for effecting such movement of the magazines comprise a pair of cams 16 which are mounted in the supporting frame 2^a. The effect of this arrangement is that when the supporting frame 2^a is swung backwardly and downwardly from its operative position, it will also carry with it the shift frame 3^a, in which the magazines are mounted, as well as the cams 16 for shifting the magazines, thereby avoiding any change in the relation of these parts existing prior to the movement of the supporting frame. The supporting frame is held in its operative position by the pins 19 mounted in the frame 17 which pins can be retracted at will to allow the frame to be rocked downward. It will be noted that in the present instance there is a distributor 11 for each of the magazines, which fact accounts for the pivotal mounting of the magazines. Of course, if but one distributor were employed, the magazines would be moved up and down bodily to locate any selected one in operative position. The employment of the two distributors, however, involves the location of the pivot 15 between and close up to the distributors, so that the operative relation between the distributors and the entrances 12 of the magazines will not be disturbed during the pivotal movement of the magazine. The frame 2^a is therefore extended up high enough to locate the pivot 15 in a convenient position. The magazine entrances 12 are mounted upon the pivots 15 so that they may be turned out of operative relation to the magazines when the latter have been swung down for removal.

In the foregoing I have shown two different embodiments of my invention, each in a different style of machine. I desire it to be understood, however, that I do not limit myself to either embodiment or to its application to either type of machine, as it is obvious that the invention is susceptible of embodiment in other forms, and is applicable to other types of machines. For instance, the form shown in Figs. 3 and 4 wherein the shift frame is mounted in the supporting frame so as to be movable to

bring one or another of its magazines into operative position, could be applied to a machine employing a single distributor instead of two distributors as shown in said figures. Furthermore, the details of construction shown in the drawings may be variously modified to suit existing conditions, those shown in the drawings being merely by way of example and more or less of a conventional nature.

Having described my invention, I declare that what I claim and desire to secure by Letters Patent is:—

1. In a typographical machine, the combination of a plurality of magazines, a supporting frame therefor mounted to swing from its normal position to permit the removal of the magazines, and means for shifting the magazines independently of such movement of their supporting frame to bring one or another into operative position. 70 80 85

2. In a typographical machine, the combination of a plurality of magazines, and a shaft frame wherein they are mounted and shiftable to bring one or another into operative position, the said frame being mounted to swing about an axis located beneath it so as to carry the magazines downwardly from their operative position for removal at the rear of the machine. 90 95

3. In a typographical machine, the combination of a plurality of magazines, a shift frame wherein they are mounted, and a supporting frame carrying said parts, the shift frame being movable toward and from the supporting frame to bring one or another of the magazines into operative position, and the supporting frame being mounted in the machine frame so as to be swung backwardly and downwardly from its normal position to carry the magazines into convenient position for removal at the rear of the machine. 100 105

4. In a typographical machine, the combination of a plurality of magazines shiftably arranged so that one or another may be brought into operative position, and a supporting frame therefor, said frame being mounted to swing about an axis located beneath the lowermost magazine so as to carry 110 115 the magazines bodily backwardly and downwardly to permit their removal at the rear of the machine.

5. In a typographical machine, the combination of a plurality of magazines facing 120 in the same direction and capable of independent use, and a supporting frame therefor, said frame being pivoted at its forward end below the middle of the magazines so as to swing the several magazines as a whole 125 backwardly and downwardly for removal.

6. In a typographical machine, the combination of a supporting frame, and a shift frame mounted thereon and carrying a plurality of magazines facing in the same di- 130

rection, the said shift frame being shiftable relatively to the supporting frame to bring one or another of the magazines into operative position, and the said supporting frame being mounted in the machine frame so as to be swung backwardly and downwardly from its operative position to permit the removal of the magazines at the rear of the machine.

7. In a typographical machine, the combination of a plurality of shiftable magazines facing in the same direction, mechanism for shifting the magazines to bring one or another thereof into operative position, and a supporting frame carrying both the magazines and their shifting mechanism, the said supporting frame being mounted to be moved backwardly and downwardly from its operative position to permit the removal

of the magazines out of the rear of the machine.

8. In a typographical machine, the combination of a supporting frame, and a plurality of magazines facing in the same direction and movable relatively to the supporting frame to bring one or another thereof into operative position, the said supporting frame being mounted so as to be swung backwardly and downwardly from its operative position to permit the removal of the magazines at the rear of the machine.

In witness whereof I have hereunto set my hand in the presence of two witnesses.

KARL RÖGER.
